UNITED STATES PATENT OFFICE.

FRANK J. TONE, OF NIAGARA FALLS, NEW YORK, ASSIGNOR TO THE CARBORUNDUM COMPANY, OF NIAGARA FALLS, NEW YORK, A CORPORATION OF PENNSYLVANIA.

ABRASIVE COATED SHEET AND METHOD OF MAKING THE SAME.

1,414,447.

Specification of Letters Patent.

Patented May 2, 1922.

Application filed May 20, 1920. Serial No. 382,804.

To all whom it may concern:

Be it known that I, FRANK J. TONE, a citizen of the United States, residing at Niagara Falls, in the county of Niagara and State of New York, have invented a new and useful Improvement in Abrasive Coated Sheets and Methods of Making the Same, of which the following is a full, clear, and exact description, reference being had to the accompanying drawing, forming part of this specification, in which—

Figure 1 is a diagrammatic side elevation showing one form of apparatus for carrying out my invention, and

Figure 2 is a diagrammatic front elevation of the same.

My invention relates to the manufacture of abrasive coated paper, cloth or other flexible sheets. These sheets, coated with abrasive grains such as those of emery or carborundum, are now used in many industries. For some purposes the flexible sheet is made up of a belt and the material to be ground or polished is brought into contact with the abrasive face of the belt when driving at high speed. The abrasive paper or cloth, when used in this manner, deteriorates, because the spaces between the abrasive grains become filled up or clogged with particles of the material being ground or abraded. As this takes place the coating surface becomes "glazed" and the belt slides over the surface without proper grinding or polishing of the same.

My invention is designed to reduce or prevent this deterioration of the sheets due to glazing or clogging with the abraded material and also to increase the life and efficiency of such sheets. The invention consists generally in applying the abrasive coating in such a way that portions of the backing sheet are left free of abrasive, thus making clearance spaces within which the ground particles of material may be received and freed from the working portions.

In these sheets as ordinarily made, the coating of abrasive grains covers the entire working surface of the paper or cloth; while under my invention the backing sheet is only coated in certain portions thereof, with an uncoated portion or portions between them.

In the drawings in which I show diagrammatically one form of apparatus for carrying out my invention, 2 represents a roll of paper to be coated, the paper passing from

this roll over idler rolls 3 and 4 to the upper surface of the glue roll 5. This glue roll dips in dissolved or melted glue of a glue tank 6. The paper is pressed against the glue roll by a pressure roll 7 which is adjustable and which determines the amount and thickness of the coating. The rolls 5 and 7 are driven by any suitable connections in the direction indicated by the arrows; and after passing around the roll 7, the abrasive is fed on the upper glue coated surface of the sheet. In the form shown, 8 is a hopper containing the abrasive grains, and having a control roller feed 9 which causes a thin sheet of the grains, indicated at 10, to fall by gravity transversely of the paper or cloth sheet traveling thereunder. In the form shown, the grains are prevented from falling on certain portions of the wet glue surface to leave clearance spaces, by means of a series of triangular deflector bars 11 mounted in a stationary frame 12 extending over and adjacent to the traveling sheet. As the falling sheet of abrasive grains strikes the deflectors, the grains are fed to the paper in separated rows. The grains striking the deflectors, will fall between them, the deflectors being spaced in any desirable manner to give the spacing desired. The paper is, therefore, coated with rows of abrasive material with clearance space between.

In the form shown, the frame is rigidly mounted, but I may impart to the deflector grating a movement transversely or diagonally back and forth across the paper in different manners to give either diagonal rows or zigzag rows of grain with spaces between them.

Other means for causing the grains to strike separated portions of the paper may be employed; for example, I may feed the abrasive grains in separated rows instead of in a continuous sheet, or I may use an intermittent feed. Thus I may employ a feed roll having spaced grooves to cause rows of the grain to fall on the paper; or I may bypass the falling sheet by deflecting vanes.

The advantages of my invention will be apparent to those skilled in the art, since the clogging or "glazing" of such abrasive sheets is reduced or prevented and the sheets given a longer life and more efficient action.

The abrasive may be applied to the surface of paper, cloth, or any flexible backing; for use on abrasive wheels and disks, for

abrasive belts, abrasive sheets, or other forms of abrasive devices. Many changes may be made in the apparatus employed for applying the abrasive, as well as in the character 5 and size of the abrasive grains themselves, without departing from my invention.

I claim:

1. The method of making abrasive sheets which consists in securing abrasive grains 10 to selected or separated portions of the face of the sheets leaving other portions uncoated.
2. The method of making abrasive sheets which consists in coating the sheets with cement and applying abrasive grains to selected 15 portions of the cemented surface, leaving alternate uncoated portions.
3. The method of making abrasive sheets which consists in coating one side of the sheet with an adhesive and applying separated rows of abrasive grains to the adhesive, leaving intermediate uncoated portions. 20
4. The method of making abrasive sheets which consists in coating one side of the sheet with adhesive and feeding separated 25 or interrupted portions of abrasive to the adhesive coated surface.

5. The method of making abrasive sheets which consists in coating one entire working surface of the sheet with an adhesive and feeding separated streams of abrasive material to the adhesive coated surface leaving intermediate uncoated portions to give grain coated portions alternating with blank portions. 30

6. As a new article of manufacture, a backing sheet having abrasive grains secured thereto in selected portions alternating with uncoated portions. 35

7. As a new article of manufacture, a flexible backing sheet having one surface coated 40 with adhesive, and separated rows of abrasive grains secured to intermittent portions of the adhesive-coated surface.

8. As a new article of manufacture, a sheet having a complete adhesive coating on one 45 face, and raised separated zones of abrasive material secured to separated portions of the adhesive coating.

In testimony whereof, I have hereunto set my hand.

FRANK J. TONE.
